L. A. ASPINWALL.
RELIEF VALVE FOR LIQUID SPRAYERS.
APPLICATION FILED AUG. 8, 1914.

1,133,785.

Patented Mar. 30, 1915.

UNITED STATES PATENT OFFICE.

LEWIS AUGUSTUS ASPINWALL, OF JACKSON, MICHIGAN, ASSIGNOR TO ASPINWALL MANUFACTURING COMPANY, A CORPORATION OF MICHIGAN.

RELIEF-VALVE FOR LIQUID-SPRAYERS.

1,133,785.

Specification of Letters Patent. Patented Mar. 30, 1915.

Continuation in part of application Serial No. 788,556, filed September 8, 1913. This application filed August 8, 1914. Serial No. 855,759.

To all whom it may concern:

Be it known that I, LEWIS AUGUSTUS ASPINWALL, a citizen of the United States, residing at Jackson, in the county of Jackson and State of Michigan, have invented an Improvement in Relief-Valves for Liquid-Sprayers, of which the following is a specification.

My present invention relates to relief valves employed in connection with liquid sprayers for spraying plants and vines, such, for example, as tomato plants and potato vines, with a suitable liquid, for killing insects which would otherwise infest and tend to destroy such vegetation, the relief or by-pass valve being employed in conjunction with a pump to care for the excess liquid not required at the nozzles of the sprayer. Heretofore this excess liquid has been taken care of in various ways. For instance, as shown in Letters Patent No. 1,018,804, granted to me February 27, 1912, for liquid sprayers, a pipe connection was employed between the pressure chamber and the suction end of the pump, by which the excess liquid not required at the nozzles was returned directly to the pump. I now prefer to employ for this purpose a loose fitting relief or by-pass valve located interiorly of the barrel or liquid receptacle and adjustable exteriorly thereof and so connected with the pressure chamber that the excess liquid not required at the nozzles is returned to the barrel or liquid receptacle, as will be hereinafter more particularly described.

In the drawing, Figure 1 is a central sectional side elevation illustrating my present invention. Fig. 2 is a central longitudinal front elevation of the same, and Fig. 3 is a sectional elevation illustrating the relationship between the relief valve, the barrel, and the pump.

Referring to the drawing, 10 indicates a portion of a barrel or liquid receptacle, such as is commonly employed in liquid sprayers to which this invention relates. As is also customary in these devices, the pressure chamber 11 is employed and connected with the discharge end 12 of a suitable pump,

from which also a pipe 13 leads to the nozzles by which the spraying is effected. Within the barrel 10 I employ an elbow 14, made of cast iron or other suitable material, and one end 15 of this elbow is connected by a pipe 16 to the pressure chamber 11, the pipe 16, as illustrated in Fig. 3, passing through one end of the barrel 10.

The elbow 14 is suitably connected to a bracket 17 having a flange 18, by means of which, together with a bolt 19, the elbow is secured in position within the barrel. 20 indicates a cylinder, preferably made of metal, which is open-ended, provided at one end exteriorly with suitable screw threads to engage the screw thread in the opposite end 21 of the elbow 14. In the cylinder 20, adjacent the end at which it is connected to the elbow 14, are a plurality of ports 22 preferably arranged circumferentially of the cylinder. Within the cylinder 20 is a piston 23, connected to which is a piston rod 24. The piston 23 is preferably loosely mounted within the cylinder 20, there being approximately a thirty-second of an inch play between the periphery of the piston and the inner surface of the cylinder, so as to simplify the construction, reduce the cost of making and fitting these parts, and also to obviate the possibility of the piston becoming corroded and rendered immovable in the cylinder during periods when the apparatus is not in use. Altogether, the working is with less power and friction by reason of the absence of packing.

Suitably secured on the rod 24 is a member having a series of radially disposed ribs 25 fitting within the cylinder and providing for intervening spaces through which the liquid may pass. Also connected to the lower or outer end of the rod 24 is a flange 26, provided at opposite sides with lugs 27 having suitable apertures in alignment therein to receive a bolt 28, which passes through the apertures in these lugs and also through apertures provided therefor adjacent the ends of the yoke 29. The lugs 27 are so spaced as to fit within the yoke 29, and these parts are secured in position by

means of cotter pins 30, which pass through the bolt 28 exteriorly of the members of the yoke or by other similar devices. The members of the yoke 29 span 5 the cylinder 20 and also the elbow 14, above which and in alignment with the cylinder, a rod 31 is suitably connected to the yoke. This rod 31 passes through an opening provided therefor in the wall of the barrel 10, and extends an appreciable distance 10 from the outer surface of the barrel.

32 designates a support base which, as illustrated, is secured to the outer surface of the barrel by means of a bolt 33, and extends 15 preferably at an inclination from the barrel.

34 is a bracket which is connected to the support base by bolts 35, or otherwise, and the free end of the bracket 34 preferably extends in a direction at right angles to 20 and approximately directly above the rod 31.

On the support base 32, there are lugs 36. A lever 37 is pivotally connected at one end to these lugs 36, and the upper end of the rod 31 is pivotally connected to the 25 lever 37 by means of a bolt 38. I also employ a spring, preferably a helical spring 39, one end of which is connected with an eye 40, in the free end of the lever 37, and the other end of which is connected with 30 an eye 41, in one end of an adjusting screw 42, which passes through the bracket 34 and on the opposite side thereof is provided with a thumb nut 43.

As will be readily understood, the action 35 of the spring 39 maintains the piston 23 in its normal position through the lever 37, the rod 31, the yoke 29, and the members connecting the same with the piston rod 24, and that upon the accumulation of an excess 40 pressure in the pressure chamber 11, the surplus liquid will pass from the discharge end of the pump, through the pipe 16, and the pressure will force the piston to move sufficiently to open the ports 22 45 through which, as well as through the open free end of the cylinder, this liquid may now pass and so be returned to the barrel. It will furthermore be apparent that the pressure at which the piston is operated may be 50 regulated by adjusting the tension on the spring 39 through the adjusting screw 42 and the thumb nut 43, it being understood that with a greater tension on the spring 39 more pressure will be required to operate 55 the piston, and vice versa, and by this means the pressure at the nozzles may be regulated when the pump is substantially constant.

I claim as my invention:

1. In a relief valve and in combination, a 60 support, a head fixed in the said support and provided with an inlet and an outlet connection, between which there is always a free passage, a cylinder secured in and

extending from the said outlet connection and provided adjacent thereto with a series 65 of discharge ports, a piston fitting loosely within the cylinder and normally lying adjacent the said outlet connection and between the same and the said discharge ports, a rod connected to the piston and extending from 70 the same to a point beyond the open free end of the cylinder, and means pivotally connected to the free end of the said rod and adjustably connecting the same to the said support exteriorly of the cylinder for regulating 75 the pressure at which the piston will operate to control the extent to which the said ports are opened by the same.

2. In a relief valve and in combination, a support, a head fixed in the said support 80 and provided with an inlet and an outlet connection, a cylinder secured in the said outlet connection and provided adjacent thereto with a series of circularly arranged discharge ports, a piston fitting loosely with- 85 in the cylinder normally placed between the said discharge ports and the said outlet connection, a rod connected to the piston, a flange connected to the rod exteriorly of the opposite end of the cylinder, a member 90 pivotally connected to the said flange, and means connecting the said member to the said support for regulating the pressure at which said piston will so operate as to control the extent to which the said ports are 95 opened by the same.

3. In a relief valve, and in combination, a support, a head secured to the said support, an inlet connection in the said head, a cylinder fixed in the said head and ex- 100 tends therefrom and provided with a series of ports adjacent the said head, a piston fitting loosely within the cylinder, a piston rod connected to the piston, a flange connected to the said piston rod exteriorly 105 of the cylinder at the free end thereof, lugs connected to the said flange, a yoke pivotally connected to the said lugs and spanning the said cylinder, and adjustable means connecting the said yoke to the said support 110 for normally maintaining the said yoke, flange, rod and piston in position and regulating the pressure at which the said piston will operate.

4. In a relief valve, and in combination, 115 a support, a head secured to the said support, an inlet connection in the said head, a cylinder fixed in the said head and extending therefrom and provided with a series of ports adjacent the said head, a piston 120 fitting loosely within the cylinder, a piston rod connected to the piston, a flange connected to the said piston rod exteriorly of the cylinder at the free end thereof, lugs connected to the said flange, a yoke pivot- 125 ally connected to the said lugs and spanning

the said cylinder, a rod connected to the said yoke, a lever pivotally connected to the end of the said rod, a bracket secured to the said support, and a spring connected between the said bracket and the free end of the said lever for normally maintaining the said rod, yoke, flange, piston rod and

piston in position and regulating the pressure at which the said piston will operate.

Signed by me this 5th day of Aug. 1914. 10

LEWIS AUGUSTUS ASPINWAL.
